UNITED STATES PATENT OFFICE.

LEE ANDERSON, OF PARIS, TEXAS, ASSIGNOR OF TWO-THIRDS TO THOMAS BROAD AND JOHN MARTIN, OF SAME PLACE.

HAME-FASTENER.

SPECIFICATION forming part of Letters Patent No. 406,497, dated July 9, 1889.

Application filed March 20, 1889. Serial No. 303,960. (No model.)

To all whom it may concern:

Be it known that I, LEE ANDERSON, a citizen of the United States, residing at Paris, in the county of Lamar and State of Texas, have 5 invented certain new and useful Improvements in Hame-Fasteners; and I do hereby declare the following to be full, clear, and exact description of the invention, such as will enable others skilled in the art to which it 10 appertains to make and use the same.

The invention has relation to hame-fasteners; and it consists in the construction and relative arrangement of parts, as hereinafter described, illustrated in the accompanying 15 drawings, and pointed out in the appended claim.

The object of my invention is to provide a fastener of the class described which is of simple construction, which can be readily 20 adjusted, and in which all strain is removed from the pivot of the locking-dog, thus obviating any breakage of the pivot, whatever 25 may be the strain.

In the drawings, Figure 1 is a side view of 25 my improved fastener; Fig. 2, a bottom view thereof, and Fig. 3 a vertical longitudinal section.

In the above-described figures of drawings, 30 A indicates a suitable casting provided with the longitudinal opening a , extending from end to end thereof, said opening being made rectangular for the reception of the bar B of corresponding shape, which fits snugly therein. The casting A is provided with the vertical cheeks b at one end, the forward edge b' of each of which is curved, as shown. Upon a pin b^2 , passing through aligned openings in the cheeks b , is pivoted a locking-dog C, through the shank c of which the said 35 40 pin passes. Said locking-dog is provided on either side with shoulders c' , the edge c^2 of which is curved to correspond with the curved edges b' of cheeks b , for a purpose presently explained.

The bar B, before mentioned, is provided 45 upon its lower face with teeth d , for a portion of its length, with which teeth is adapted to engage the nose c^3 of the locking-dog, the casting A being provided with the opening 50 a' , through which project the teeth d . For

maintaining said nose in engagement with the teeth, I provide a coiled spring D, located in rear of the pivot b^2 and between the shank of the locking-dog and the partition d' of the casting.

In order that the locking-dog may be readily manipulated to release the bar B when it is desired to adjust the same, said locking-dog is provided with a finger-piece E, and to prevent the accidental disengagement of these parts, as well as to afford a support for the fingers of the hand when operating the dog, I provide the casting A with a guard F.

To limit the movement of the bar B in one 65 direction, I provide the latter upon its lower face with a stop B' , which will abut against the edge a^2 of the casting.

For attaching the hames, I provide one end of the bar B with a hook f , and provide the 70 casting A with a like hook f' .

When it is desired to tighten the hames, all that is necessary is to slide the bar B in the direction indicated by the arrow, the nose of the locking-dog in this movement riding 75 over the teeth of the bar B.

For loosening the hames, the dog C is operated through the finger-piece to release the teeth, and the bar A then drawn outward through the opening for the desired distance, 80 when the dog is released, the coiled spring causing the nose of the dog to again engage the teeth of bar B.

It will be seen that when the bar is locked in position the curved edges of the shoulders 85 on the locking-dog bear against the like edges of the cheeks b of the casting, and all strain is therefore removed from the pivot-pin.

Having now described my invention, what I 90 claim as new is—

In a hame-fastener, the combination, with the casting A, having the longitudinal rectangular opening a , the opening a' on the under side thereof, the depending cheeks b , 95 provided with the curved edges b' , the hook f' , and the guard F at the forward end of said casting, of the rectangular bar B, toothed upon its under side, passing through the opening a and provided with the hook f at its 100

rear end, and the stop B', the locking-dog C, pivoted upon the pivot b^2 , between the cheeks b , and provided with the shoulders c' , having the curved edges c^2 abutting against the curved edges b' , the nose c^3 , engaging the teeth of the bar B, the forwardly-projecting finger-piece E, and the rearwardly-projecting shank c, and the coiled spring D, located between the shank

c and the partition d' of casting A, substantially as described.

In testimony whereof I affix my signature in presence of two witnesses.

LEE ANDERSON.
